Int. Cl. D6—01

U.S. Cl. D15—1

FIG. 1 is a front perspective view of a chair in accordance with my design;

FIG. 2 is a rear perspective view thereof;

FIG. 3 is a side elevational view thereof;

FIG. 4 is a front perspective view of a modified design of the chair of FIG. 1;

FIG. 5 is a rear perspective view of the chair embodiment shown in FIG. 4; and

FIG. 6 is a side elevational view thereof.

The characteristic feature of the design is its backrest portion.

This application is a continuation of my earlier filed applications Serial Nos. D-16,645 and D-16,637 filed April 9, 1969, and now abandoned.

I claim:

The ornamental design for a chair, substantially as shown and described.
